US00D991912S

(12) **United States Design Patent** (10) **Patent No.:** **US D991,912 S**
(45) **Date of Patent:** **** Jul. 11, 2023**

(54) **WIRELESS EARPHONE**

(71) Applicant: **Shenzhen Grandsun Electronic Co., Ltd.**, Shenzhen (CN)

(72) Inventors: **Zhangliang Xiong**, Shenzhen (CN); **Dejun Jiang**, Shenzhen (CN); **Lei Cao**, Shenzhen (CN); **Xin Chi**, Shenzhen (CN); **Guixiao He**, Shenzhen (CN); **Shiwen Guo**, Shenzhen (CN); **Haiquan Wu**, Shenzhen (CN)

(73) Assignee: **Shenzhen Grandsun Electronic Co., Ltd.**, Shenzhen (CN)

(**) Term: **15 Years**

(21) Appl. No.: **29/807,141**

(22) Filed: **Sep. 9, 2021**

(30) **Foreign Application Priority Data**

Aug. 13, 2021 (CN) 202130525464.5

(51) **LOC (14) Cl.** **14-01**

(57) **CLAIM**

The ornamental design for a wireless earphone, as shown and described.

DESCRIPTION

FIG. 1 is a front perspective view of a wireless earphone of the present disclosure;

FIG. 2 is a rear perspective view thereof;

FIG. 3 is a bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof;

FIG. 10 is a front perspective view of a wireless earphone according to another embodiment of the present disclosure;

FIG. 11 is a rear perspective view thereof;

FIG. 12 is a bottom perspective view thereof;

FIG. 13 is a front elevational view thereof;

FIG. 14 is a rear elevational view thereof;

FIG. 15 is a left-side elevational view thereof;

FIG. 16 is a right-side elevational view thereof;

FIG. 17 is a top plan view thereof; and,

FIG. 18 is a bottom plan view thereof.

1 Claim, 18 Drawing Sheets
